(57) **CLAIM**

The ornamental design for a gyroscope fidget, as shown and described.

DESCRIPTION

FIG. 1 is a front perspective view of the gyroscope fidget, showing my new design;

FIG. 2 is a rear elevation view thereof;

FIG. 3 is a front elevation view thereof;

FIG. 4 is a right-side elevation view thereof;

FIG. 5 is a left-side elevation view thereof;

FIG. 6 is a bottom plan view thereof; and,

FIG. 7 is a top plan view thereof.

The dash-dot-dash broken lines in the drawings depict portions of the gyroscope fidget in which the design is embodied that form no part of the claimed design.

1 Claim, 7 Drawing Sheets
